(57) **CLAIM**

The ornamental design for an automobile body, as shown and described.

DESCRIPTION

FIG. 1 is a front view of an automobile body constructed according to my novel design;

FIG. 2 is a right side view thereof;

FIG. 3 is a left side view thereof;

FIG. 4 is a rear view thereof;

FIG. 5 is a top plan view thereof;

FIG. 6 is a front right elevational perspective view thereof;

FIG. 7 is a rear elevational perspective view thereof;

FIG. 8 is a front view of another embodiment of an automobile body constructed according to my novel design;

FIG. 9 is a right side view of the automobile body of FIG. 8;

FIG. 10 is a left side view of the automobile body of FIG. 8;

FIG. 11 is a rear view of the automobile body of FIG. 8;

FIG. 12 is a top plan view of the automobile body of FIG. 8;

FIG. 13 is a front right elevational perspective view of the automobile body of FIG. 8; and,

FIG. 14 is a rear left elevational perspective view of the automobile body of FIG. 8.

The broken lines showing of environmental structure in FIGS. 1-14 of the drawings are for illustrative purposes only and form no part of the claimed design.
